FOUNTAIN PEN

Filed Dec. 6, 1930

WITNESS:

LOUIS R. YOKOYAMA
INVENTOR

BY *Victor J. Evans*

ATTORNEY

UNITED STATES PATENT OFFICE

LOUIS R. YOKOYAMA, OF NEW YORK, N. Y.

FOUNTAIN PEN

Application filed December 6, 1930. Serial No. 500,642.

This invention relates to fountain pens and more particularly to a fountain pen of the self-filling type.

The primary object of the invention is to construct a fountain pen of simple and practical form, so that the filling of the ink reservoir may be accomplished with great facility, and for this purpose the invention comprehends the use of a conventional form of dropper as an ink reservoir within the barrel of the pen, whereby the usual rubber ink sack is eliminated and a glass reservoir substituted therefor which is less subject to deterioration and capable of ready replacement by the user whenever necessary.

Another object of the invention is to construct the barrel of the fountain pen so that the same will include a gauge whereby the amount of ink in the reservoir may be readily determined by the user in advance of the complete exhaustion of the ink supply, which has been a defect of fountain pens as heretofore constructed.

Still further objects are to simplify and improve the construction of fountain pens generally and to reduce the cost of manufacture thereof, and to provide a fountain pen which will be extremely practical and convenient to use.

Other objects and advantages of the invention will be hereinafter specifically pointed out, or will become apparent, as the specification proceeds.

With the above indicated objects in view, the invention resides in certain novel constructions and combinations and arrangement of parts, clearly described in the following specification and fully illustrated in the accompanying drawings, which latter show embodiments of the invention as at present preferred.

In the drawings:

Fig. 1 is a view of the present fountain pen in side elevation.

Fig. 2 is a vertical sectional view through the pen taken on the line 2—2 of Fig. 1.

Fig. 3 is a detail view of the rearward end of the pen with the rear cap removed, illustrating the sight gauge; and

Fig. 4 is a transverse sectional view

through the barrel of the pen at the sight gauge, taken on the line 4—4 of Fig. 2, looking in the direction of the arrows.

Referring to the drawings the fountain pen in this instance includes a barrel 10 having a rearward portion 11 of reduced diameter for reception of the rear cap 12. The front end of the barrel is equipped with a stem 13, in which stem there is fitted an ink feed member 14, which latter may be of conventional form.

The stem 13 has a shank portion 15, to which is fitted a tubular member 16, which may be of rubber or like material. A glass dropper 17, which may be of conventional form, is inserted within the rubber tubular member 16 with an air-tight fit between the body of the dropper and the interior of the tubular member 16, with the discharge end 18 of the dropper in proximity to the ink channel 19 of the feed 14. The dropper is desirably secured in place within the barrel by means of a packing ring 20 placed about the neck portion 21 of the rubber bulb 22.

With the parts assembled as described, the pen is filled by immersing the nib portion 23 in the ink and compressing the bulb 22. Thereupon, the ink will be drawn into the dropper body 17. The rear cap 12 is then applied to the reduced portion 11, thereby protecting the bulb 22 against accidental compression. As the pen is used, the ink will flow from the discharge end 18 of the dropper to the ink passage 19 of the feed 14. An important feature of the invention resides in the provision of an air chamber 31 around the discharge end 18 of the dropper to promote attraction of the ink from the dropper body 17 to the ink passage 19.

After the pen has been used a short time, it may be desirable to inspect the ink supply, and for this purpose the rearward portion 11 of the barrel is provided with a cut-out portion at opposite sides, here indicated at 24 and 25. With the cap 12 removed, and the pen held in writing position, the ink supply within the dropper body 17 may be readily inspected, as seen in Fig. 3. When it is found that the supply of ink has dropped to such an extent that the ink is not visible

through one of the sight gauge apertures 24 and 25, the user may seek a convenient opportunity to replenish the supply, and thus there is little likelihood of the ink supply becoming exhausted.

5 To protect the nib 23 when the pen is not in use the barrel 10 is provided with a closure cap 30 of substantially conventional form.

10 Considerable particularities of description, as to materials, part details, dimensions, capacities and utilities may have been herein indulged in, but it will be understood that these statements, made with particular reference to that one, and the one now preferred, 15 of the many possible embodiments of the invention which is illustrated in the drawings, are not in any way to be taken as definitive or limitative of the invention. Inasmuch as many changes could be made in the above construction, and many apparently widely different embodiments of the invention could be made without departing from the scope thereof, it is intended that all matter contained in the above description or shown in 20 the accompanying drawing shall be interpreted as illustrative and not in a limiting sense.

It is also to be understood that the language contained in the following claim is intended to cover all the generic and specific 30 features of the invention herein described, and all statements of the scope of the invention which, as a matter of language, might be said to fall therebetween.

35 In other words, the scope of protection contemplated is to be taken solely from the appended claim, interpreted as broadly as is consistent with the prior art.

What I claim as new is:

40 A fountain pen including a barrel open at its rearward end and having a stem, a hollow feed member and a nib secured in said stem, a resilient tubular member secured to said stem, a removable reservoir positioned 45 in said resilient tubular member, said reservoir including a non-collapsible ink holding cylinder gripped by said resilient tubular member and having a reduced diameter portion disposed in said tubular member, there 50 being an air space extending from one end of said reduced portion and beyond the same and communicating with the interior of said hollow feed member, a collapsible suction member at the opposite end of said cylinder 55 and extending beyond the rearward open end of said barrel, a locking ring between said collapsible suction member and said barrel, and a cap for the rearward end of said barrel, said cap adapted to be positioned over 60 said collapsible suction member.

In testimony whereof I hereby affix my signature.

LOUIS R. YOKOYAMA.
